PRESSURE REGULATOR FOR UNDERWATER BREATHING APPARATUS

Samuel G. Lecocq, Huntington Park, Calif., assignor to Pittman Products, Inc., Huntington Park, Calif., a corporation of California

Filed Aug. 15, 1969, Ser. No. 18,694

Term of patent 14 years

Int. Cl. D23—01

U.S. Cl. D83—1

FIG. 1 is a perspective view of a pressure regulator for underwater breathing apparatus embodying my new design;

FIG. 2 is an end view of the end not shown in FIG. 1;

FIG. 3 is a side elevational view of the side not shown in FIG. 1;

FIG. 4 is a bottom plan view.

I claim:

The ornamental design for a pressure regulator for underwater breathing apparatus, substantially as shown.
